UNITED STATES PATENT OFFICE.

WINTHROP LINCOLN FAY, OF DEXTER, MAINE.

LATHE-TURRET.

1,151,004.

Specification of Letters Patent. Patented Aug. 24, 1915.

Application filed April 19, 1915. Serial No. 22,249.

To all whom it may concern:

Be it known that I, WINTHROP LINCOLN FAY, of Dexter, in the county of Penobscot and State of Maine, have invented certain new and useful Improvements in Lathe-Turrets, of which the following is a specification.

My invention relates to turret lathes and particularly to certain improvements in the construction of the turret patented to Norman H. Fay by Letters Patent No. 639,892 dated Dec. 26, 1899. In the lathe referred to the turret was turned from one position to the next position in order by the single reciprocal operation of a hand lever. The motion of this lever in one direction unlocked the turret and the motion in the opposite direction rotated it to a new position and locked it there. Another motion of the same lever clamped it firmly in place in its new position. The mechanism included a central stud on which the turret was journaled, the turret having on its under side a locking ring with external notches and internal teeth and a horizontally disposed turret locking bolt adapted to engage the external notches. On the upper end of the stud was a nut connected with an operating handle and above the nut and secured to the stud was a disk having a notch engaged by a locking bolt on the lever. At the lower end of the stud was a turret revolving cam having a cam surface formed to disengage the locking bolt from the external notches of the locking ring and carrying a pawl for engaging the internal teeth of the ring.

According to my present invention I make the stud stationary with a nut and its handle lever at its upper end; the turret revolving cam instead of being secured to the lower end of the stud I now secure to the lower end of a sleeve which fits over the fixed stud. The locking bolt on the hand lever instead of engaging a disk on the upper end of the stud now engages a notch in the upper end of the sleeve which carries the turret revolving cam. Again, the pawl carried by the cam instead of engaging internal ratchet teeth formed in the ring is now so located as to engage the same notches which are engaged by the turret locking bolt. Finally, the locking bolt at the base of the turret which in my former machine extended out horizontally into the space required for turning large diameters, is now inclined so

as to bring its outer end as far as possible away from the axis of the lathe.

My invention may best be understood by reference to the accompanying drawing in which is shown a turret and its connecting parts constructed in accordance with my present invention.

In the drawing Figure 1 is a central vertical section on the line $x-x$ of Fig. 3, Fig. 2 is a section on the line $x-x$ of Fig. 1, Fig. 3 is a section on the line $y-y$ of Fig. 1, Fig. 4 is a plan of the turret revolving cam, Fig. 5 is a section on the line $x-x$ of Fig. 4, Figs. 6 and 7 are elevations and plan of the pawl, Fig. 8 is a plan of the ring and Fig. 9 is a section on the line $x-x$ of Fig. 8.

Referring to the drawing, the slide 1 carries a fixed upright stud 2 over which fits a sleeve 3. The turret 4 is mounted so as to turn on the sleeve 3. The stud 2 has on its upper end a nut 5 to which is connected the handle lever 6 having the hand controlled spring locking bolt 7. The nut 5 extends over and incloses the upper end of the sleeve and in the latter is formed a notch or opening to receive the inner end of the bolt 7.

On the lower end of the turret is secured the ratchet ring 8 having exterior notches 9, the ring being positioned to surround and inclose the turret revolving cam 10 which is secured to the lower end of the sleeve 3 beneath the turret and within a space formed in the top of the slide. The turret locking bolt 11 is slidably mounted in the slide and its inner end engages the external notches 9. The lower portion of the inner end of the bolt 11 extends well down below the lower surface of the ring so that it may be acted upon to be released by the cam 10 which is secured as stated, to the lower end of the sleeve 3.

The outer end of the bolt 11 is located at a lower level than the inner end in order to leave as much space as possible between it and the lathe center and interfere as little as possible with the use of the lathe on large work.

The operative portion of the cam 10, designated as 10^a, lies just below the ring 8 and it is so formed that when it is rotated its operative edge will strike the inner end of the bolt 11 and force it out of engagement with the notch 9.

The cam 10 has pivoted to it in a radial recess 10^b a pawl 12 formed with an up-

wardly extending dog 12^a on its end this dog being formed and positioned so as to enter the notches 9 from the under side.

The general principles upon which my lathe are constructed and its mode of operation are the same as in the former patent referred to and the parts which I have omitted to specifically describe are substantially the same.

10 In operating the turret the lever is pushed back to release the nut and the movement is continued until the bolt 7 engages the opening in the upper end of the sleeve. The lever is now pushed back turning the cam 5 until it strikes the inner end of the bolt 11 and disengages it from the notch 9. When this takes place, the pawl 12 will have reached a point directly beneath one of the notches the pawl and the operative portion 20 of the edge of the cam being spaced apart the same distance as the interval between the notches. The lever is now reversed, the pawl snaps into its notch from the under side and the ring and turret are turned until 25 the bolt 11 snaps into the next notch. The bolt 7 is now withdrawn from engagement with the sleeve by the action of the thumb piece 13 and the nut is tightened by a further movement of the lever. The turret is 30 thus firmly clamped in position until the next change is made.

The improved construction which I have shown and described in the lathe makes it stronger, simpler and less expensive to build 35 and the result is a much more efficient tool.

I claim;

1. In a turret lathe, the combination of a slide, a vertically disposed stud thereon, a nut on the upper end of said stud, a handle 40 for operating said nut, a sleeve fitting over said stud, a hand controlled latch bolt in said handle adapted to engage the upper end of the sleeve, a turret journaled on said sleeve, a ratchet ring on the under side of 45 said turret, having external notches, a spring-pressed locking bolt adapted to engage said notches, a turret revolving cam secured to the lower end of said sleeve, said cam being formed and positioned to disengage 50 said locking bolt and a pawl carried by said cam for engaging said ratchet ring.

2. In a turret lathe the combination of a slide, a vertically disposed stud thereon, a nut on the upper end of said stud, a handle

lever for operating said nut, a sleeve fitting 55 over said stud, a hand controlled bolt in said handle lever adapted to engage the upper end of said sleeve, a turret journaled on said sleeve, a ratchet ring on the under side of 60 said turret having external notches, a spring-pressed locking bolt adapted to engage said notches, a turret revolving cam secured to the lower end of said sleeve, said cam being formed and positioned to disengage 65 said locking bolt and a pawl carried by said cam beneath said ring for engaging said notches.

3. In a turret lathe the combination of a slide, a vertically disposed stud thereon, a nut on the upper end of said stud, a handle 70 lever for operating said nut, a sleeve fitting over said stud, a hand controlled bolt in said handle lever adapted to engage the upper end of said sleeve, a turret journaled on said sleeve, a ratchet ring on the under 75 side of said turret having external notches, a spring pressed locking bolt adapted to engage said notches, a turret revolving cam secured to the lower end of said sleeve, said cam being formed and positioned to disengage 80 said locking bolt and having therein a radial slot, a pawl pivoted in said radial slot positioned to engage said notches from the under side of the ring.

4. In a turret lathe the combination of a 85 slide, a vertically disposed stud thereon, a nut on the upper end of said stud, a handle lever for operating said nut, a sleeve fitting over said stud, a hand controlled bolt on said handle lever adapted to engage the upper 90 end of said sleeve, a turret journaled on said sleeve, a ratchet ring on the under side of said turret having external notches, a spring pressed locking bolt adapted to engage 95 said notches, said bolt inclining downwardly from its inner to its outer end, a turret revolving cam secured to the lower end of said sleeve, said cam being formed and positioned to release said locking bolt and a pawl carried by said cam for engaging 100 said ratchet ring.

In testimony whereof I have affixed my signature, in presence of two witnesses.

WINTHROP LINCOLN FAY.
